UNITED STATES PATENT OFFICE.

CHARLES C. FIELDS, OF MORRISTOWN, TENNESSEE.

COMBINATION-TOOL.

No. 888,795.

Specification of Letters Patent.

Patented May 26, 1908.

Application filed March 6, 1908. Serial No. 419,531.

To all whom it may concern:

Be it known that I, CHARLES C. FIELDS, a citizen of the United States, residing at Morristown, in the county of Hamblen and State 5 of Tennessee, have invented a new and useful Combination-Tool, of which the following is a specification.

This invention relates to combination tools.

10 The object of the invention is to provide an article of this character which shall present, in a simple and compact form, a pocket knife and a pipe wrench, the parts being so disposed relatively to each other that one 15 may be used without interfering with the other in any particular.

With the above and other objects in view, as will appear as the nature of the invention is better understood, the same consists, generally stated, in a pocket knife having its blade spring extended beyond the handle to provide a fixed wrench jaw, and its side plates provided with ears, and a second wrench jaw pivoted between the ears and co- 25 acting with the fixed jaw.

The invention consists, further, in a pocket knife having its blade spring extending beyond the handle and toothed to provide a fixed wrench jaw, and its side plates extended laterally to provide ears, a second wrench jaw pivoted between the ears and co- 30 acting with the fixed jaw, and a spring secured to the blade spring and engaging the pivoted jaw to cause it normally to lie close to the fixed jaw.

The invention consists, further, in a pocket knife having its blade spring extended beyond the handle and toothed to provide a wrench jaw, and its side plates provided with 40 lateral ears, a second wrench jaw pivoted between the ears and provided with a fingerhold, and a spring secured to the blade spring and engaging the inner face of the fingerhold.

The invention consists, further, in the 45 various novel details of construction of a combination tool, as will be hereinafter described and claimed.

In the accompanying drawings forming a part of this specification, and in which like characters of reference indicate corresponding parts, Figure 1 is a view in perspective of a combined knife and pipe wrench, constructed in accordance with the present invention. Fig. 2 is a vertical longitudinal section through the implement, the blade of the knife being shown closed. Fig. 3 is a

transverse sectional view, taken on the line 3—3 of Fig. 2.

Referring to the drawings, 1 designates, generally, the handle of a knife, and 2 the blade thereof. The handle, as usual, is composed of two side plates 3, two grips 4, and a blade spring 5, the latter being held assembled with the grips and side plates by rivets 6. As shown in Fig. 2, the blade spring at 65 the butt end of the handle is transversely widened, and extends beyond the handle to provide a fixed wrench jaw 7, the outer face of which is curved and toothed in a manner common to such elements. At the butt end 70 of the handle, the jaw 7 is secured to the side plates by rivets 8, which latter, as shown in Fig. 1, extend outwardly beyond the butt end of the handle, and are laterally extended therefrom to provide ears 9.

Pivoted between the ears 9 is a second wrench jaw 10, the operative face of which is straight and oppositely toothed relatively to the jaw 7, and is provided with a fingerhold 11, the jaw being held in position between the ears by a rivet 12. In order to cause the jaw 10 normally to occupy the position shown in Fig. 1 relatively to the jaw 7, a leaf spring 13 is provided, one end of which is secured to the blade spring by a rivet 14, and the other 85 end of which extends between the ears 9 and bears against the inner face of the fingerhold.

It will be seen from the drawings, that, in the use of the wrench, the knife blade may remain closed, so that all danger of the user 90 injuring himself will be prevented, and, further, that the use of the knife blade will not require any shifting of the parts of the wrench.

As a matter of further improvement, one of 95 the side plates at the blade end of the handle may be extended to provide a screw-driver 15.

The improvements herein defined, while simple in character, will be found thoroughly effective for the purposes designed, and will 100 coact in the production of a thoroughly efficient and durable implement.

I claim:—

1. A pocket knife having its blade spring extended beyond the handle to provide a 105 fixed jaw and its side plates provided with ears, and a second wrench jaw pivoted between the ears and coacting with the fixed jaw.

2. A pocket knife having its blade spring 110 extending beyond the handle and toothed to provide a fixed wrench jaw, and its side

plates extended laterally to provide ears, a second wrench jaw pivoted between the ears and coacting with the fixed jaw, and a spring secured to the blade spring and engaging the pivoted jaw to cause it normally to lie close to the fixed jaw.

3. A pocket knife having its blade spring extended beyond the handle and toothed to provide a wrench jaw, and its side plates provided with lateral ears, a second wrench jaw pivoted between the ears and provided with

a fingerhold, and a spring secured to the blade spring and engaging the inner face of the fingerhold.

In testimony that I claim the foregoing as 15 my own, I have hereto affixed my signature in the presence of two witnesses.

CHARLES C. FIELDS.
